UNITED STATES PATENT OFFICE.

ROBERT ZAHN, DECEASED, BY ALFRED RIETZSCH, ADMINISTRATOR, OF PLAUEN,
GERMANY.

FABRIC-TENSION MECHANISM FOR EMBROIDERING MACHINES.

1,148,811.

Specification of Letters Patent.

Patented Aug. 3, 1915.

Application filed February 9, 1914. Serial No. 817,498.

To all whom it may concern:

Be it known that I, ALFRED RIETZSCH, a subject of the German Emperor, and a resident of Forststrasse 1, Plauen, Germany, 5 am administrator of the estate of ROBERT ZAHN, deceased, who was a subject of the German Emperor, and that said ROBERT ZAHN did invent the new and useful Improvement in Fabric-Tension Mechanism 10 for Embroidering-Machines, of which the annexed is a specification.

The longer and higher embroidering machines are built, the more difficult it becomes to stretch or tension sufficiently taut the 15 fabric surface which correspondingly increases in size. Hitherto the fabric has been stretched by directly imparting motion to the fabric roller through the medium of a coarsely notched disk which was turned 20 by an iron bar. By reason of the coarseness of the notches of that disk and the direct transmission of movement to the fabric roller, a sufficiently fine adjustment of the fabric roller was impossible.

25 The object of the present invention is to provide means whereby the aforesigned drawback will be avoided.

My invention will be fully understood by reference to the accompanying drawing, in 30 which similar reference characters denote corresponding parts and in which—

Figure 1 is an elevation of a part of the tambour frame and the fabric roller showing my new mechanism for tensioning the 35 fabric and Fig. 2 is a side elevation thereof.

Rotatively mounted in the tambour frame *a* are the toothed wheels *b*, *b* which are provided with square pivots *c* that engage central notches *d* provided in the heads *e* of the 40 fabric roller *f*. At each end the fabric roller is centrally loosely borne on the axles of the wheels *b*. Meshing with each wheel *b* is a smaller toothed wheel *g* fixed on a rotary spindle *h* which is arranged parallel 45 to the axle of the wheel *b* and is also suitably borne in the tambour frame.

Fixed on the spindle *h* is a ratchet wheel

i with which coöperates a pawl *j* fulcrumed at *i'* in a bracket *k* of the tambour frame. The ratchet wheel *i* is formed integrally 50 with the usual coarsely notched disk *i*² which is adapted to be turned as hitherto by an iron bar (not shown).

It will be obvious, that, notwithstanding the coarseness of the notches of the disk *i*², 55 the fabric roller now could receive a fine adjustment to produce the desired tautness of the fabric, by reason of the interposition of the intermediate small gear, which at the same time permits a much greater force to 60 be exerted on the fabric roller to stretch the fabric.

What I claim and desire to secure by Letters Patent is:

1. In an embroidering machine, the combination with a tambour frame and a fabric roller carried by the latter, of a tensioning device for the fabric, comprising a coarsely notched disk, a ratchet wheel connected to said disk, a pawl coöperating with said 65 wheel and transmission gears between said disk and the fabric roller, said notched disk serving for the engagement of a hand bar to impart movement thereto.

2. In an embroidering machine, the combination with a tambour frame and a fabric roller carried by the latter, of a tensioning device for the fabric, comprising a coarsely notched disk, a ratchet wheel connected thereto, a pawl coöperating with 75 said wheel, a small pinion connected to said disk and a larger pinion connected to said roller and meshing with the smaller pinion, the said notched disk serving for the engagement of a hand bar to impart move- 80 ment thereto.

In testimony whereof I affix my signature in presence of two witnesses.

ALFRED RIETZSCH,
Attorney, Plauen, administrator of Robert
Zahn, deceased.

Witnesses:

JOSEF GRANZ,
ROBERT H. NEIR.
